Primary Examiner — Karen S Acker(74) *Attorney, Agent, or Firm* — Nixon & Vanderhye P.C.(57) **CLAIM**

The ornamental design for a “patterned textile fabric,” as shown and described.

DESCRIPTION

This patent or application file contains at least one drawing executed in color. Copies of this patent or patent application publication with color drawing(s) will be provided by the Office upon request and payment of the necessary fee.

The sole FIGURE is a plan view of a patterned textile fabric showing our new design, wherein the different shading represents color contrast.

The broken lines in the drawing represent environmental subject matter that forms no part of the claim.
